United States Patent Office

Des. 198,542
Patented June 30, 1964

198,542

RECORDING TABLET DISPENSER

Samuel Tapper, 440 Baldwin Road,
Maplewood, N.J.

Filed Aug. 21, 1961, Ser. No. 66,424

Term of patent 14 years

(Cl. D52—2)

FIG. 1.

FIG. 2.

FIG. 3.

FIG. 1 is a top perspective view of a recording tablet dispenser, showing my new design;

FIG. 2 is a side elevational view thereof;

FIG. 3 is a bottom plan view thereof.

I claim:

The ornamental design for a recording tablet dispenser, as shown.
